UNITED STATES PATENT OFFICE.

WILLIAM B. FLANAGAN, OF BROOKLYN, NEW YORK.

VEGETABLE RECEPTACLE.

Application filed May 2, 1928. Serial No. 274,608.

The invention relates to improvements in receptacles for use in kitchens, pantries, etc., for holding numerous kinds of vegetables, separated from each other and readily accessible.

The object of the invention is to provide a device of the class set forth which may be easily and inexpensively manufactured, on account of extreme simplicity of construction, yet will be highly efficient and in every way desirable.

With the foregoing in view, the invention resides in the novel subject matter herein-after described and claimed, description being accomplished by reference to the accompanying drawing.

Fig. 1 is a perspective view.

Fig. 2 is a vertical transverse section.

Fig. 3 is a detail longitudinal section on line 3—3 of Fig. 2.

Fig. 4 is a disassembled perspective view.

Fig. 5 is a horizontal section on line 5—5 of Fig. 2.

In the drawing above briefly described, the numeral 6 denotes two front standards and 7 has reference to two rear standards, all of said standards being of one-piece angle metal formation. Secured by spot welding, or other desired means against the inner sides of the standards 6—7, are two rectangular end sheets 8 of "metal cane" or other desired sheet material. The upper and lower ends of the sheets 8 are bound by channel-shaped metallic strips 9—10 respectively, and the strips 9 are held tightly in place by hooks 11 formed by inwardly bending the upper ends of four of the flanges of the standards 6—7.

A plurality of baskets 12 extend between the end sheets 8 and have their ends closed by these sheets. Each basket 12 is formed primarily from a single sheet of "metal cane" or the like, said sheet being bent into trough form and providing the basket with a vertical back wall 13, with a narrow bottom 14, and with a front wall 15 which inclines forwardly. The upper edges of the back and front walls 13—15, are provided with channel-shaped metal bindings 16—17. Rivets 18 pass through the binding 16 and through the portion of the basket-forming sheet embraced thereby, and secure the upper rear corners of the basket to the four inwardly projecting flanges of the standards 7. Other rivets 19 secure the rear lower corners of the basket wall 13 to said flanges, and rivets 20

secure the binding 17 and the contained portion of the front wall 15, to the inwardly projecting flanges of the standards 6. Thus, the standards 6—7 support the entire weight of the baskets 12 and their contents, and the end sheets 8 merely form ends for said baskets, and cooperate with the bindings 9—10 in holding the standards 6 in properly spaced relation with the standards 7.

Preferably, the upper ends of the flanges to which the walls 13—15 are secured, are provided with extended portions 11^a bent downwardly around the bindings 16—17, forming hooks or claws similar to the parts 11. This construction not only gives a smooth finished formation at the upper corners of the entire receptacle, but assists in producing a rigid structure.

In the construction shown, the upper edges of the back walls 13 are spaced below any overlying basket to provide for additional circulation of air, and it will be obvious that the construction is such as to permit free entrance of air at the front of the cabinet, as well as through the numerous perforations of the "metal cane." Moreover, attention is invited to the forward inclination of the front wall 15 of the lowermost basket, permitting the insertion of a brush or broom beneath the entire receptacle for sweeping up any earth and the like which may sift through from the vegetables.

Preferably, the upper basket 12 is provided with a transverse partition 21 of "metal cane" or the like. The upper edge of this partition is bound as at 22 and the ends of the binding are secured in any desired manner to the bindings 16—17, said ends being denoted at 23. The lower edge of the partition 21 is provided with a channel-shaped sheet metal binding 24 in whose bight portion, a wire 25 is disposed. The ends of this wire pass through the front wall 15 and the rear wall 13 and are clinched as at 26, thereby effectively anchoring the lower end of the partition.

On account of the advantages existing for the details disclosed, they are preferably followed. However, within the scope of the invention as claimed, variations may be made.

I claim:

1. A vegetable receptacle comprising two parallel vertically elongated end walls of sheet metal each provided throughout its height with two parallel inwardly project-

ing reinforcing flanges disposed at its front and rear edges respectively, and a plurality of one-piece metal sheets each bent to provide an open-ended and open-top basket member, each of said basket members having a vertical back and a forwardly inclined front, the latter being provided throughout the length of its upper edge with a vertical stiffening portion, the end portions of said basket members being received between said reinforcing flanges of said end walls and abutting the latter, whereby said walls and basket members co-operate in forming complete baskets, means securing said backs of said basket members to the rearmost of said flanges, and means securing said vertical stiffening portions of said basket members to the foremost of said flanges, whereby said end walls and basket members are held in rigid relation.

2. A vegetable receptacle comprising two front and two rear angle metal standards, two one-piece metallic end sheets lying against the inner sides of said standards, channel-shaped metal bindings for the upper and lower ends of said sheets, the ends of said bindings and the vertical edges of said sheets being secured to said standards, holding the latter in spaced relation; a plurality of one-piece sheets each bent to form an open-ended trough-shaped basket having its ends closed by said end sheets, each basket having a vertical rear wall and a forwardly inclined front wall, the upper edges of said back and front walls being provided with channel-shaped metallic bindings, means securing the upper and lower portions of each rear wall and the binding of the latter to the rear standards, and means securing the upper front corners of each front wall and the binding of the latter to the front standards.

3. A vegetable receptacle comprising two front and two rear angle metal standards having integral extensions at the upper ends 45 of their flanges, two one-piece metallic end sheets lying against the inner sides of said standards, channel-shaped metal bindings for the upper and lower ends of said end sheets, certain of said extensions being 50 downwardly clinched around the uppermost bindings, and the edge portions of said sheets being secured to said standards, holding the latter in spaced relation; a plurality of one-piece sheets each bent to form an 55 open-ended trough-shaped basket having its ends closed by said end sheets, each basket having a vertical rear wall and a forwardly inclined front wall, the upper edges of said rear and front walls being provided with 60 channel-shaped metallic bindings, means securing the upper and lower portions of each 65 rear wall and the binding of the latter to the rear standards, and means securing the upper front corners of each front wall and the binding of the latter to the front standards, the remainder of the aforesaid extensions being downwardly clinched around 70 said rear and front bindings.

4. In a vegetable receptacle embodying a 75 basket having front and rear walls connected by a bottom, and a transverse partition between said front and rear walls and secured at its upper portion thereto; a channel-shaped metallic binding for the lower edge 80 of said partition, and a wire extending longitudinally in the bight portion of said binding, the ends of said wire being passed through the lower portions of said back and front walls and clinched, thereby anchoring the lower end of the partition.

In testimony whereof I have hereunto affixed my signature.

WILLIAM B. FLANAGAN.
